UNITED STATES PATENT OFFICE

CHARLES KOLODNY, OF BROOKLINE, MASSACHUSETTS

DESIGN FOR A COMBINATION BATH CHAIR AND CABINET

Application filed August 25, 1932. Serial No. 44,696. Term of patent 7 years.

To all whom it may concern:

Be it known that I, CHARLES KOLODNY, a citizen of the United States, residing at Brookline, in the county of Norfolk and State of Massachusetts, have invented a new, original, and ornamental Design for a Combination Bath Chair and Cabinet, of which the following is a specification, reference being had to the accompanying drawing, forming a part thereof.

I claim:

The ornamental design for a combination bath chair and cabinet as shown.

CHARLES KOLODNY.
